ATTORNEY

UNITED STATES PATENT OFFICE.

ABNER F. CALLISON, OF PHILADELPHIA, PENNSYLVANIA.

COUPLING DEVICE.

Application filed July 25, 1923. Serial No. 653,743.

To all whom it may concern:

Be it known that I, ABNER F. CALLISON, a citizen of the United States, residing at Philadelphia, in the county of Philadelphia and State of Pennsylvania, have invented a new and useful Coupling Device, of which the following is a specification.

This invention relates to a coupling device, which is especially adapted for coupling portable units or containers to railroad flat cars, automobile trucks or the like.

An important object of the invention is to provide an improved coupling device for this purpose, which will securely hold the container against lateral movement when loaded on the car or truck, and yet will readily permit the transfer of the container to or from suitable ramp tracks, which are provided at the warehouse or freight yard.

It is also an object of the invention to provide an improved retaining device, which will assist in the transfer of the portable unit to or from the ramp tracks, and which may be readily coupled to or uncoupled from the portable unit, while the latter is at any point on the ramp track, so that no exterior force is needed for the loading or unloading operation.

In carrying out my invention, I prefer to provide two couplers for each unit or container, the latter being so constructed as to cooperate with the coupling members, and snugly receive the same when loaded. The principles of the invention, and the preferred structure by means of which they are carried out will be best understood from the following detailed description taken in connection with the accompanying drawings.

In the drawings:

Figure 1 is a side elevation of a flat car with the unit containers being delivered to the ramp tracks.

Figure 2 is a plan view thereof.

Figure 3 is an end elevation of two flat cars on parallel tracks, with the ramp track beds shown in section.

Figure 4 is a central vertical section through the coupling device with a portion

of the container floor in position to receive the same.

Figure 5 is a section taken on the line 5—5 of Figure 4.

Figure 6 is a detail view of a bottom plate to which the coupling is secured.

Figure 7 is a detail sectional view through the three-way valve or stop cock.

The numeral 10 indicates a railroad flat car, of the usual construction, and adapted to receive for transportation a number of unit containers 11. These containers extend throughout the width of the car and may be of any length desired, but, as herein shown, they are of suitable size so that four units may be loaded onto one flat car. In providing for the loading and unloading of the unit containers 11 any number of side tracks 12 may be provided, depending upon the volume of business handled, and adjacent these tracks there are provided ramp track beds 13 which support the ramp tracks 14, which slope downwardly at their forward ends, as shown at 15. The tracks 14 are arranged at either side of the tracks 12, and are in position to receive small spaced rollers 16 which are journaled in either side of the unit containers 11, and normally overhang the sides of the flat car when the container is loaded for transportation.

Each unit container is provided with a floor 17 which is secured to a plurality of I beams 18 or the like, and a plate 19 of sheet steel is riveted to the underside of the I beams. Midway between the ends of the container and near each side thereof, the plate 19 is provided with a circular opening 20 within which fits a steel plate 21, which is riveted to the plate 19 and to the adjacent I beams, as shown at 22. The steel plate 21 is provided with a central opening 23, the lower part of which is outwardly flared as at 24, so that it may be more easily engaged by the coupling member carried by the car.

The car 10 is constructed with a platform 25 supported in the usual manner by I beams 26 or the like, and in order to

equip the car especially for receiving the unit containers it is provided with a number of cast steel tubular housings 27 suitably spaced, so as to register with the openings 5 23 to lock the unit containers in position when loaded for transportation. Each of the housings 27 is provided with an enlarged portion 28, adapted to be received between the I beams 26 to retain the housing in 10 proper position, while the upper end of the housing is tapered as shown at 29, in order that the same may more readily engage and enter the opening 23. When the container has 15 been loaded onto the car platform 25, the steel plate 19 will be in contact with the car platform, while the upwardly projecting portion of the housing 27 will fit snugly within the opening 23 and reach upwardly to the undersurface of the floor 17. When 20 the container, however, rests upon the horizontal portion of the ramp tracks 14, the steel plate 19 will be above the upper end of the housing 27, so that the car may be readily pulled out from underneath the 25 same.

The operation of the coupling member, which is used for transferring the unit container to and from the ware house platform, will now be described. For this purpose a 30 heavy steel sleeve or pipe section 30 is slidably mounted within the housing 27, and is supported by a bottom plate 31 secured to the lower end of the housing 27 by screws 32, or the like. The bottom plate is provided centrally with a threaded boss 33, on which is mounted a cylinder 34 which is slightly spaced from the inner wall of the pipe section 30. The cylinder 34 receives a piston 35, which normally rests upon the 35 boss 33, and is provided with a stem or rod 36 adapted to telescope within a tubular member 37 supported centrally of a head 38, which is threaded to the upper end of the pipe section 30. The tubular member 37 and 40 stem 36 are surrounded by an expansile coiled spring 39, and the relative outward movement of the telescoping members is limited by a head 40 formed on the upper end of the stem 36, which is adapted to engage the inturned flange 41 at the lower end 45 of the tubular member 37. The bottom plate 31 is provided centrally with a threaded opening 42, to which is connected a pipe 43 adapted to supply compressed air 50 underneath the piston head 35 to raise the same, and thereby through the pressure of the spring 39 to project the pipe section 30 and head 38, as shown in dotted lines in 55 Figure 4. When the piston is thus actuated, 60 the air within the upper portion of the cylinder 34 is expelled between the outer wall of the cylinder and the inner wall of the pipe section 30, and through ports 44 formed in the upper face of the bottom 65 plate 31. The upward movement of the pis-

ton head 35 is limited by a ring 45 threaded inside of the upper end of the cylinder 34.

When the unit container is to be unloaded, compressed air is admitted through the pipe 43 into the lower end of the cylinder 34, and 70 the car is then shunted between a pair of ramp tracks 14. As the container is raised by the ramp tracks, the pipe section 30 is projected by the compressed air and follows the floor 17 of the container, engaging the 75 side of the opening 23 to advance the container on the ramp tracks to the point desired. When the container reaches the desired position, the air pressure is removed from beneath the piston head 35 allowing the plunger to drop to the position shown in full lines in Figure 4, whereupon the car 80 may be withdrawn. In loading the container, the car is moved underneath the same until the coupler is approximately beneath the opening 23 when the compressed air is turned on, and the plunger projected against the bottom of the container. The car is slowly moved until the plunger enters the opening 23. The upper end of the plunger is tapered, as shown at 45, to facilitate the projection thereof and its engagement with the opening 23. As the container rides down the inclined portions 15 of the ramp 85 tracks, the inclined portions 24 of the opening 23 are guided over the inclined edge 24 of the housing 27 causing the latter to enter the opening 23, and the container gradually settles upon the platform of the car, whereupon the compressed air may be released 90 from the cylinder 34.

The compressed air, which is admitted through the pipe 43, may be supplied from the air-brake system of the train. To this end, the pipe 43 is connected to a hose 46, which may be coupled to a similar hose on an adjacent car, or to the air-brake line on the same car, or it may be carried to the engine. Means must be provided at some point in the line for turning the air on or off from the cylinder 34. By way of illustration, I have shown a three-way valve or stop cock 47, which, as shown in detail in Figure 7, comprises a housing 48 within which is rotatably mounted a stem 49, controlled by a handle 50. A passageway 51 extends through the stem 49, and in the position shown in full lines in Figure 7, admits the air to the pipe 43. If the stem be rotated 90° to the position shown in dotted lines, the outlet from the pipe 46 is closed, while the pipe 43 is exhausted through a port 52 which leads to the atmosphere.

From the foregoing description, it will be seen that I have provided a coupling device which positively retains the several units against sidewise movement during transportation, and which may be conveniently operated to facilitate the transfer of the units to or from the ramp tracks. The 130

coupling device is also constructed so that there are no projecting parts on the container, and the latter when delivered to the ware house platform is in position for easy loading, with the floor thereof closely adjacent to the floor of the ware house.

While I have shown and described the specific details of one construction in which the invention may be embodied, it is to be understood that this is merely illustrative and that various modifications may be made therein without sacrificing any of the salient features of the invention as embodied in the appended claims.

15. What is claimed is:

1. In a device of the character described, the combination of a vehicle having a platform with fixed upstanding projections, a removable unit container normally resting on the platform and having sockets receiving said projections to prevent relative horizontal movement of said container, and a member optionally projectable vertically above each fixed projection to maintain the connection between the vehicle and the container as the latter is raised from the platform.

2. In a device of the character described, the combination of a vehicle having a platform with fixed upstanding tubular housings, a removable unit container normally resting on the platform and having sockets receiving said housings to prevent lateral displacement of said container, a member reciprocably mounted in each of said housings, and means for projecting said member above the housing to maintain engagement with the corresponding socket while the container is raised above the platform.

3. In a device of the character described, the combination of a vehicle having a platform with fixed tubular housings projecting upwardly therefrom, a removable unit container normally resting on the platform and having sockets receiving said housings to prevent lateral displacement of the container, a member reciprocably mounted in each housing and normally held within the same by gravity, and means for yieldably projecting said members above the housings to maintain engagement of said members with the sockets while the container is raised above the platform.

4. In a device of the character described, the combination of a vehicle having a platform with fixed upstanding projections, a removable unit container normally resting on the platform and having sockets receiving said projections to prevent lateral displacement of said container, a member projectable vertically above each fixed projection to maintain the connection between the vehicle and the container while the latter is raised above the platform, and pneumatic means for controlling the position of said projectable member.

5. In a device of the character described, the combination of a vehicle having a platform with fixed upstanding projections, a removable unit container normally resting on the platform and having sockets for receiving said projections, a member optionally projectable vertically above each fixed projection to prevent lateral displacement of the container with respect to the vehicle when the container is raised from the platform, the mouths of said sockets and the terminal portions of said fixed projections and optionally projectable members being correspondingly tapered to facilitate their interengagement.

6. In a device of the character described, the combination of a platform having a fixed tubular housing projecting vertically from its surface, a sleeve reciprocably mounted within the housing, a cylinder mounted within the sleeve and secured in fixed relation to the housing, a piston operable in the cylinder and having a connection with the upper end of said sleeve, and means for introducing fluid pressure underneath the piston to raise the same and project the sleeve above the tubular housing.

7. In a device of the character described, the combination of a platform having a fixed tubular housing projecting vertically from its surface, a sleeve reciprocably mounted within the housing and having a tapered head closing its upper end, a cylinder mounted within and spaced from the sleeve and secured to the lower end of said housing, a piston operable in the cylinder and having a connection with the upper end of said sleeve, and pneumatic means for optionally raising the piston to project the sleeve above the tubular housing.

8. In a device of the character described, the combination of a platform having a fixed tubular housing projecting vertically from its surface, a sleeve mounted for reciprocation within the housing and having a tapered head closing its upper end, a cylinder mounted within and spaced from the sleeve and secured to the lower end of said housing, a piston operable in the cylinder and having a yielding telescoping connection with the head of said sleeve, and means for introducing fluid pressure underneath the piston to raise the same and yieldingly project the sleeve above the tubular housing.

9. In a device of the character described, the combination of a vehicle having a platform with a fixed upstanding projection, a unit container normally resting on the platform and having a socket receiving said projection, and a member optionally projectable above the fixed projection to maintain the connection between the vehicle and the container as the latter is raised from the platform.

10. The combination with a container pro-

vided with an opening having a flared portion, of a vehicle having a platform to support the container, a fixed tubular housing projecting from the platform to engage said opening of the container, said housing having its upper end tapered, and a movable member carried by the housing and pro-

jectable above the upper end of the housing in the same opening, said member having a tapered upper end.

In testimony that I claim the foregoing as my own, I have hereto affixed my signature.

ABNER F. CALLISON.
